RECLINING CHAIR

Filed Aug. 6, 1928

Inventor

Albert L. Harris.

By Frank C. Karmard, Attorney

UNITED STATES PATENT OFFICE

ALBERT L. HARRIS, OF BAY CITY, MICHIGAN, ASSIGNOR TO KELTON AURAND MANUFACTURING CO., OF BAY CITY, MICHIGAN, A CORPORATION OF MICHIGAN

RECLINING CHAIR

Application filed August 6, 1928. Serial No. 297,717.

This invention relates to chairs, and particularly to chairs such as used in motor busses, aeroplane and other passenger carrying vehicles.

5 The prime object of the invention is to design a chair having an adjustable back, and provide simple and economical means for adjusting the inclination thereof.

Another object of the invention is to provide a simple, substantial and effective adjusting means, which can be readily operated to the chair occupant, and which is adaptable to chairs provided with double seats, as well as a chair with a single seat.

15 A still further object is to design an adjusting mechanism composed of few parts, positive in operation, and which will not get out of order.

The above and other objects will appear as 20 the specification progresses, reference being had to the accompanying drawing in which I have shown the preferred embodiment of my invention, and in which like reference numerals indicate like parts throughout the 25 several views thereof.

In the drawing.

Fig. 1 is a side view of my improved chair with the adjusting mechanism in place thereon.

20 Fig. 2 is a rear view thereof.

Fig. 3 is an enlarged part sectional view showing the adjustable mechanism, the dotted lines showing the back in an adjusted position and the hand lever depressed.

25 Fig. 4 is a plan detail view of the link.

Referring now to the drawing, the numeral 5 indicates the frame of the chair which can be covered with wicker, cloth, leather, or any other desired material, this is formed of 30 seamless tubing and is provided with the usual arms 6, and a back frame 7 is hingedly connected to the main frame at 8, said hinging point being preferably at a point approximately in line with the top of the seat cushion.

45 The chair shown in the accompanying drawing is formed of tubing as above described, and is designed to accommodate two people, and each side is therefor equipped with an adjusting mechanism so that each 50 back frame may be adjusted to suit its par-

ticular occupant, without in any manner disturbing the occupant of the opposite seat.

The adjusting mechanism proper comprises a tubular member 9 which is slidably mounted in the arm of the chair, spaced apart 55 teeth 10 being provided on the under side thereof, the end of said member having a tongue 11 which is adapted to be pivotally secured to a link member 12 by means of a rivet 13, the end of said link being formed with spaced apart legs 14 adapted to receive the said tongue therebetween. The opposite end of the link 12 is provided with a tongue 15, and the back frame is slotted as shown at 60 16 to receive it, a rivet 16^a serving to pivotally connect said tongue to said back frame.

A tubular member 17 is rigidly welded or otherwise secured to the main frame, and the locking mechanism is mounted therein, and comprises a vertically disposed latch 18, the end 19 of which is beveled to engage the teeth in the member 9 and hold it in adjusted position, a coiled spring 20 being provided in said member, and is interposed between the latch and a plug 21, so that an upward pressure is exerted on the latch at all times, the plug being removably secured in any approved manner, so that the spring and latch can be removed for repairs or any other purpose.

70 A laterally projecting hand lever 22 is secured to the latch as shown, and projects through a slotted opening 23 provided in the member 17, said lever preferably being positioned directly below the arm so that it will 75 not catch the clothing nor project into the seating area, and when it is desired to adjust the back the seat occupant presses down on the lever 22 to disengage the latch from the teeth and the back frame can be inclined as 80 desired.

85 From the foregoing description it will be obvious that I have perfected a very simple, economical, and convenient adjustable chair which is very easy to adjust and operate.

90 What I claim is:—

An adjustable chair comprising a seat frame, tubular posts on the rear end thereof, a back frame pivotally connected thereto, hollow tubular arms on said seat frame and 95

formed with downwardly projecting tubular extensions, the lower ends of which are secured to the front of said tubular posts, hollow tubular members slidably mounted therein, links pivotally connected to said members at a point beyond the end of the arms and to the back frame respectively, a latch mounted in said seat frame, a plug, a spring interposed between said latch and plug, and a lever for actuating said latch to disengage it from said toothed member.

In testimony whereof I hereunto affix my signature.

ALBERT L. HARRIS.
